UNITED STATES PATENT OFFICE.

JOHN E. DREW, OF JERSEY CITY, NEW JERSEY, ASSIGNOR TO WADE & BUTCHER CORPORATION, OF JERSEY CITY, NEW JERSEY, A CORPORATION OF NEW JERSEY.

DESIGN FOR A HUNTING KNIFE.

Application filed February 23, 1923. Serial No. 5,240. Term of patent 14 years.

To all whom it may concern:

Be it known that I, JOHN E. DREW, a citizen of the United States, residing at Jersey City, in the county of Hudson and State of New Jersey, have invented a new, original, and ornamental Design for Hunting Knives, of which the following is a specification, reference being had to the accompanying drawing, forming part thereof.

Figures 1 and 2 are respectively side and rear edge views, showing my new design.

I claim:

The ornamental design for a hunting knife, as shown.

In testimony whereof, I have signed my name to this specification.

JOHN E. DREW.
